UNITED STATES PATENT OFFICE.

OTTO REINHARDT, OF EASTON, PENNSYLVANIA, ASSIGNOR TO THE FIRM OF R. & H. SIMON, OF UNION HILL, NEW JERSEY, AND EASTON, PENNSYLVANIA.

WARP STOP-MOTION FOR LOOMS.

SPECIFICATION forming part of Letters Patent No. 759,309, dated May 10, 1904.

Application filed February 24, 1902. Serial No. 95,196. (No model.)

To all whom it may concern:

Be it known that I, OTTO REINHARDT, a citizen of the United States, residing at Easton, Northampton county, State of Pennsylvania, have invented certain new and useful Improvements in Warp Stop-Motions for Looms, of which the following is a specification.

My invention relates to looms, and has for its object to provide a simple and efficient construction for stopping the loom in case one of the warps should break.

The invention will be fully described hereinafter and the features of novelty pointed out in the appended claims.

Reference is to be had to the accompanying drawings, in which—

Figure 1 is a plan of a loom provided with my improved stop-motion with parts omitted for the sake of greater clearness. Fig. 2 is a 20 sectional elevation on line 2 2 of Fig. 1. Fig. 3 is a detail plan of part of the dropper-holders. Fig. 4 is another detail of the dropper-holders drawn upon an enlarged scale. Figs. 5 and 6 are sectional elevations showing the 25 warp, dropper, and dropper holder or guide in two different positions. Fig. 7 is a cross-section on line 7 7 of Fig. 1. Fig. 8 is a cross-section on line 8 8 of Fig. 1. Fig. 9 is a sectional elevation showing the same parts as Fig. 30 7, but in a different position; and Fig. 10 is a cross-section on line 8 10 of Fig. 1, showing the parts in a different position from that represented in Fig. 8.

On the frame members 1 of the loom are 35 carried brackets 2, which support a cross-bar 3. To this bar are secured hangers 4, which at their upper ends carry a horizontal bar 5, on which the warps 6 are adapted to rest side by side, as indicated particularly in Figs. 3 40 and 4. For the sake of clearness I have in Figs. 2 and 7 shown the warps slightly above the bar 5; but it will be understood that they rest thereon normally. To the cross-bar 3 are secured, as by bolts 7, a series of dropper-holders or dropper-guides 8, which extend 45 parallel with the bar 3 and are spaced from each other by distance-pieces 9. Upon each

of the warps 6 is supported a dropper 10, preferably made in the shape of a hairpin, and the said droppers are arranged to straddle the 50 holders or guides 8, as shown best in Figs. 2 to 6 and 9. Normally—that is, when the warps 6 are stretched—the droppers 10 will be held in an upper position, as clearly shown in Figs. 2 and 5. Should, however, any one of the 55 warps break, the corresponding dropper will fall until its upper bend rests on the guide 8 below it, and the lower end of such dropper will then project into the path of mechanism, to be described presently, for actuating the 60 stop device. The lower ends of the hangers 4 carry a cross-bar 11, to which are secured rigidly, as by angle-irons 12, guides 13 of approximately rectangular shape. In these guides is adapted to reciprocate from front 65 to rear a slide or carrier 14, provided with rigid arms 15, projected forwardly therefrom. These arms are pivotally connected with links 16, which are joined to rocking arms 17, pivoted at 18 upon suitable stationary hangers 19, 70 and each driven by a cam or eccentric 20 on the shaft 21. For this purpose each of the arms 17 is provided with a shoe 22, engaging the eccentric 20 and held against the same by a weight 23. It will be understood that as 75 the shaft rotates the slide or carrier 14 will be reciprocated in the guides 13.

At each end of the carrier 14 are arranged posts 24, receiving a pivot-rod 25, upon which are loosely mounted trip-bars 26, weighted at 80 their lower portions, as indicated at 27 in Fig. 2. The trip-bars will therefore stand normally in a vertical position, as shown in Figs. 2 and 7. In this position each trip-bar holds up an actuating-dog 28, pivoted at the front 85 part of the slide or carrier 14, as shown at 29. The trip-bars 26 are so arranged that normally the droppers 10 are not in the path of said trip-bars. Should, however, one of the droppers be in its lower position, owing to the 90 breakage of a warp 6, such dropper will project into the path of the corresponding trip-bar 26, and as the trip-bars reciprocate with the carrier 14 such bar will come in contact

with the projecting dropper and will be rocked on its pivot 25, as indicated in Fig. 9. This will allow the dog 28 to drop into its operative position.

Upon brackets 30, projected from the bar 11, is journaled a rock-shaft 31, which is provided with arms 32, located in the path of the dogs 28 when said dogs are in their dropped position. As long, however, as a dog is in its elevated position it passes over the corresponding arm 32 without touching it. In the construction shown there are three trip-bars 26, three dogs 28, and three arms 32. Fig. 1 shows three trip-bars with the dogs and arms belonging to two of them. I desire it to be understood, however, that I may employ only one trip-bar, if desired, or any other suitable number of them. It is preferable to have a plurality of trip-bars, so that the weight of the parts to be moved by the dropper 10 in its lower position may be reduced.

The shaft 31 carries a lever 33, adapted to engage a stop 34. Stops 35 may also be provided for each of the arms 32, although these stops are not necessary. With the lower end of the lever 33 is connected a cord or wire 36, which leads under a guide-pulley 37, journaled in a stationary bracket 38, and then extends upward in a cylindrical casing 39 to a plunger 40, working in said casing. A spring 41 has a tendency to keep the plunger in its upper position, and therefore to throw the shaft 31 rearward until the lever 33 engages the stop 34. The plunger 40 has a stem 42 projecting forwardly and provided with guide-pins 43, engaging slots 44 in the casing 39, so as to prevent a turning movement of the plunger. The stem 42 is provided with an obliquely-disposed arm 45 at its upper end. This stem and arm constitute together a spring-pressed member for operating a stop mechanism.

So far I have described those parts which constitute my invention and which are capable of attachment to any ordinary loom, the shaft 21 being one of the counter-shafts of the loom. The arm 45 is the element which operates the stop mechanism, and in the construction shown said stop mechanism is one well known in the art as a weft stop-motion—that is, a mechanism which operates to stop the loom in case the weft breaks. By the action of the arm 45 said mechanism becomes a warp stop-motion also, as will fully appear hereinafter. I desire it to be clearly understood, however, that the specific construction of the stop mechanism, consisting of the parts numbered from 46 upward, is not my invention, but is one well known in the art, and I claim such mechanism only generically as combined with certain other elements named in the claims and not in its specific details.

Upon the shaft 21 is located a cam 46, which imparts an oscillating motion to an elbow-lever 47, fulcrumed at 48. The upper end of

this lever is provided with a hook 49. This hook is adapted to engage a corresponding hook 50 on a lever 51. This lever has at its rear end the customary wires 52, which are adapted to be engaged by the weft-thread, so that the lever 51 will be swung up, as shown in Fig. 8, sufficiently to make the hook 50 clear the hook 49. This of course will happen only as long as the weft-thread strikes the wires 52 properly. When, however, the weft-thread is broken, the hook 50 will remain down and will therefore be caught by the hook 49 upon the forward movement of the latter. The lever 51 is fulcrumed at 53 upon an arm 54, adjustably secured in a socket 55. This socket is carried by a rod 56, adjustable in sockets 57 in a direction practically at a right angle to the adjustment of the arm 54. The sockets 57 are carried by a plate 58, fulcrumed at 59 to a stationary part of the loom, so that the entire structure formed by the said plate 58, the rod 56, and the arm 54 can swing forward and rearward in a horizontal plane, together with the hook 50. A spring 60 normally keeps the said structure in its rearmost position. When the two hooks 49 and 50 interlock, owing to the breakage of the weft 61, the entire structure above defined is swung forward on its pivot 59, and a projection 62 at the forward portion of the plate 58 shifts a releasing-lever 63, pivoted at 64, upon a stationary part of the loom. This releasing-lever has a projection 65, which bears against the starting-lever 66 below its pivot 67. Thus when the releasing-lever is shifted forward against a stop 68 the starting-lever 66 is thrown over into the stop position, it being understood that said lever is connected with the usual belt-shifter or any other starting device. The operation thus described is the usual operation of the weft stop-motion illustrated in the drawings. Now in case one of the warps should break one of the droppers 10 will fall, causing the trip-bar 26 to swing on its pivot 25 and allowing the corresponding dog 28 to drop. This dog will then engage the corresponding arm 32 and rock the shaft 31. The lever 33 will then through the medium of the cord or wire 36 pull down the plunger 40, and thus bring the arm 45 against the lever 51, causing the hook 50 to be moved into the path of the hook 49, whereupon the loom will be stopped, as above described.

While I have described in detail a particular construction of my improved stop-motion, I desire it to be understood that the construction described is only an example of the many possible modes of execution of my invention, and I do not intend to limit myself to such specific constructions.

While I have referred to the U-shaped pins 10 under the name of "droppers," for the reason that they are arranged to drop upon the breakage of the corresponding warp-threads, these

pins may be designated more broadly as "warp-engaging elements," which are movable transversely of the warps, but held normally stationary thereby, and which when released by the breakage of a warp will move from their normal position into an active position, in which they are adapted to operate the stop mechanism.

I claim as my invention—

1. The combination, with substantially U-shaped droppers arranged to be normally supported by the warps, of guides straddled by the thread-receiving bends of said droppers and arranged to limit their downward movement, the said droppers being removable by simply lifting them off the guides and warps, and both ends of the droppers extending freely at the sides of the guides and projecting beneath said guides when the droppers are lowered, and a stop mechanism arranged to be operated by either end of a lowered dropper.
2. The combination of warp-engaging elements movable transversely of the warps and normally held in position thereby, each of said elements being arranged to move transversely of its warp when the latter breaks, a plurality of independent trip-bars each corresponding to a group of said elements and adapted to be shifted by engagement with any one element of the group which may be out of its normal

position, and a stop mechanism actuated by the shifting of any one of the said trip-bars.

3. The combination of a stop-mechanism, a sliding spring-pressed member adapted to operate said mechanism, warp-engaging elements normally held stationary by the warps but adapted to move transversely thereof when released by the breaking of a warp, a flexible connection attached to said spring-pressed member, and means, operated by the released warp-engaging elements, for pulling said connection and moving the said member against the tension of its spring.

4. The combination of a stop mechanism, a sliding spring-pressed member adapted to operate said mechanism, warp-engaging elements normally held stationary by the warps but adapted to move transversely thereof when released by the breaking of a warp, a flexible connection attached to said spring-pressed member, a rock-shaft to which the other end of said flexible connection is attached, and means, operated by the released warp-engaging elements, for throwing said rock-shaft to pull said connection and move the said member against the tension of its spring.

OTTO REINHARDT.
